ALEXANDER HAY NISBET, OF LONDON, ENGLAND

ROTATABLE GRIP MECHANISM

Application filed January 14, 1930, Serial No. 420,804, and in Great Britain October 11, 1929.

The present invention relates to improvements in or relating to rotatable grip actuating mechanism of the Bowden type, of the kind in which the twist grip has a tubular helically slotted extension which is rotatable in a split sleeve clamped on the outside of the handle bar and the sleeve is provided outside the twist grip and its covering with guiding means for a longitudinally movable slide which is connected to the Bowden cable or the like and is engaged by the helical slot of the extended portion of the grip to cause the slide to be moved to and fro to actuate the cable or the like according to the direction of rotation of the grip.

A feature of the present invention is the provision on the forward portion of the sleeve of a movable cover for the purpose of exposing the slide in its forward position to facilitate the attachment and detachment of the cable or the like. This cover is preferably of the sliding type but it may also be mounted on a hinge or the like.

Another feature is an improved construction of rotatable grip actuating mechanism of the kind above referred to which, while conducting to manufacturing economies shall give a strong, simple and dependable device having the power of adjustment to control the ease of rotation of the hand grip. Thus in a rotatable grip actuating mechanism of the kind above referred to, the grip is provided with a helical slot or like of quick pitch to engage with an appropriately shaped projection depending from a slide which is received in a closed topped axial slot or way formed or provided in a sleeve which surrounds such front extension of the rotary grip, and this outer sleeve has its front or inner portion adapted to be clamped to the handle bar or like member by appropriately increasing the thickness of such front portion to suit the diameter of the handle bar or like member, and the rear or outer por-

tion is adapted to be tightened upon the tubular extension of the twist grip.

A form of outer sleeve which serves well for the purpose of the present invention is a one-part clamp sleeve comprising a nearly complete tubular portion having, at the front portion, laterally projecting ears or lugs through which a tangent screw or screw nutted bolt is passed to secure the sleeve to the handle bar or the like, and having along the rear portion similar ears or lugs with co-operating tightening screw or bolt whereby to draw the rear portion into frictional contact with the tubular extension of the grip with a desired amount of pressure according to the frictional resistance required.

To increase the thickness of such front portion of the outer sleeve so as to enable such front portion to grip the handle bar or the like, it is convenient and advantageous to fit within such front portion a liner in the form of a one-part clamp having laterally projecting ears or lugs to register with those of the front portion and co-operate with the tangent screw or bolt thereof, such liner being preferably held to definite position by means of a steady-pin character.

As an alternative to increasing the thickness of the front portion of the sleeve the latter may be so formed that the front portion is of reduced diameter.

The rotating grip is preferably held against longitudinal movement by abutting against a portion of the sleeve or liner at one end and by a clamp on the handle bar against which it abuts at the other, but it may also be so held within the sleeve by a projection on one part fitting in a slot or recess on the other, or it may be retained against longitudinal movement on the handle bar in either direction by means of a clamp or other suitable means.

In a variant form the upper part of the sleeve may be split from end to end, and the two parts held together by a cover slid over

the after portion and engaging the two parts. Such engagement may conveniently be effected by bending back the edges of each part to engage with such cover.

5 In order that the present invention may be the more readily understood reference is hereinafter made to the constructional example illustrated in the accompanying drawings, in which:—

10 Fig. 1 is a longitudinal section through the twist grip which is shown mounted on a handle bar or like carrier tube.

Fig. 2 is a perspective view of the slide and grip receiving sleeve.

15 Fig. 3 is a perspective view of the rotary grip.

Figs. 4 and 5 are perspective views of a liner for the front portion of the outer sleeve and the end clamp respectively.

20 Fig. 6 is a perspective view of a bearing washer which may project over the end of the clothing of the grip.

Fig. 7 is a perspective view of the slide and

25 Fig. 8 is a perspective view of the movable cover which is applied to close an opening made in the top of the front end of the slide-guide for exposing the corresponding end of the slide.

Figs. 9 and 10 show a variant form of slide 30 and grip receiving sleeve made in two parts, and Figs. 11 and 12 longitudinal and transverse sectional views of a sliding piece which holds the two pieces of such variant sleeve together.

35 Referring to the accompanying drawings, 1 is the twist grip which may be made from metal sheet bent into tubular form and has a suitable rubber or other clothing 2 secured thereto such as by springing a sheath of rubber tightly thereover. The grip 1 has a front tubular extension 3 which is provided with a helical slot or the like 4 of quick pitch, this slot being adapted to be engaged by a suitably shaped projection 5 of a sliding strip or block 40 6 hereinafter referred to.

The tubular extension 3 is received in the rear or outer portion 7 of a clamp sleeve 8 which is formed from a metal sheet bent into tubular form and has at the front portion 9 50 lateral ears or projections 10 to receive a tangent tightening screw or bolt 11. The thickness of such front portion 9 is increased as shown by a liner 12 conveniently made from sheet metal bent nearly into the form of a 55 tubulus with lateral ears or projections to register with the ears or projections 10 and to co-operate with the tangent screw 11, the length of such liner 12 being such as to form an end abutment for the tubular extension 60 3 of the grip 1.

In forming the outer one-part clamp sleeve 8 the metal is raised to form an axial groove or way 13 which forms the slide-guide for the slide 6.

65 Preferably the groove or way 13 termi-

nates a short distance from the front end of the sleeve 8, and for a short distance the top of the front end of the slideguide or way 13 is cut away, and a slot 14 is cut through the end of the sleeve 8 in line with the longitudinal medial line of the way 13.

70 The open topped portion 15 of the way 13 is of such a length that when a suitably shaped cover 16 is removed, a key-hole slot 17 in the slide 6 is exposed when such slide is at the limit of its inward displacement by the helically slotted extension 3 of the grip 1.

75 Preferably the sides of the open topped portion 15 of the way 13 are bent outwardly so as to frictionally cooperate with the cover 16 which is of somewhat dove-tailed shape in cross-section, such cover having a forward channelled shaped part 18 to extend over the corresponding end of the outer sheath 19 of a Bowden cable, such end of the outer sheath of the Bowden cable abutting against the end of the front portion 9 of the sleeve 8, while the inner member 20 lies in the slot 14 and has its headed end 21 received flush in the wider portion of the key-hole slot 17, this method of 80 coupling a Bowden wire to a slide forming however, no part of the present invention as it is in accordance with an expired Patent No. 17777/13.

85 Along the rear portion 7 of the clamp sleeve 8 which is formed so as to leave a longitudinal gap 21^a when formed into a nearly complete tube, is provided with further ears or lugs 22 by which with the aid of a co-operating tightening screw or bolt 23 such rear portion 7 can be tightened upon the tubular extension 3 of the grip 1 to control the ease of 90 rotation of the grip.

95 The rotary grip 1 is held from axial movement in either direction by the abutment formed by the inner edge of the thicker front portion 9 of the clamp sleeve 8 on the one hand, and such as by an outer one-part clamp 100 24 of pressed sheet metal on the other abutting against the outer end of the grip 1 and frictionally secured to the handle bar or like member by lateral lugs or ears 25 and co-operating screw 26.

105 Flanged bearing washers 24^a may be conveniently and advantageously fitted over the 110 ends of the clothing 2 of the grip 1.

115 In one example of manufacturing the outer sleeve 8, this may be pressed from sheet metal an appropriate blank permitting the metal to be raised to form an axial groove or way 13 which is open at both ends and permitting the front portion of the blank to be doubled on itself to form a front clamping portion 9 of the required thickness, and the whole to be shaped to clamp and sleeve form including medial clamping means 22 integral with the sleeve 8 for tightening this upon the tubular extension 3 of the rotary grip 1 for varying the resistance of rotation thereof.

120 In order to conform to varying diameters 130

of handle bars or like members, the internal diameter of any standard grip component 8 may be varied by the insertion of appropriately disposed liners such as 12 which may be held to definite position by means of a steady pin character such as lugs 25^a on the linings 12, engaging notches 26^a in the end or ends of the component 8.

Other appropriate means may be provided for varying the resistance of rotation of the rotary grip, for example, a clamp to grip a portion of the rotary grip, such clamp being held from rotation such as by a clip or hook engaging a clamp which grips the handle bar or like member.

In the variant shown in Figs. 9 to 12, the upper part of the clamp sleeve 8 is split from end to end thus comprising two parts 27, 28 having lateral projections 29, 30. The two parts are secured together at the top by a cover 31 slid over the after portion of the sleeve in engagement with the projections 29, 30. The forward open-topped portion of the way in the sleeve is covered by the sliding cover 16 similar to that shown in Fig. 8 which is used with the construction illustrated in Figs. 1 to 8.

The construction herein described is notably favourable to manufacturing economies inasmuch as the parts can be cheaply pressed from sheet metal, and involves notably few parts, thereby effecting a saving in raw material as well as in the number of operations necessary for manufacture, also the attachment and detachment of the Bowden cable to or from the slide is very much facilitated, the inner or front portion of the closed topped axial slot or groove being so opened by the removal of a slide, clip or other cover as to expose the corresponding end of the slide for engaging or disengaging the power transmission mechanism without interfering with any other part of the rotary grip device as operatively secured on the handle bar or like member.

The term "transmission mechanism" is used in the claims hereof to denote that type of mechanism known in the trade as Bowden mechanism consisting of an inextensible inner member or cable and an incompressible outer member or sheath.

What I claim is:—

1. A grip control of the kind described comprising a rotary grip having a tubular helically slotted extension; a split sleeve in which said tubular helically slotted extension rotates adapted to be clamped on the outside of a carrier member; a guide in said sleeve outside the twist grip; a longitudinally movable slide working along said guide adapted to permit a transmission mechanism to be detachably connected therewith, said slide being engaged by the helical slot of said tubular extension and moved thereby on rotation of said rotary grip to actuate the cable;

of the transmission mechanism; and a movable cover at the forward end of said clamp sleeve to expose the slide for attachment or detachment of said transmission mechanism while the slide remains operatively related to the grip.

2. A grip control of the kind described comprising a rotary grip having a tubular helically slotted extension; a split sleeve in which said tubular helically slotted extension rotates adapted to be clamped on the outside of a carrier member; a guide in said sleeve outside the twist grip; a longitudinally movable slide working along said guide adapted to permit a transmission mechanism to be detachably connected therewith, said slide being engaged by the helical slot of said tubular extension and moved thereby on rotation of said rotary grip to actuate the cable of the transmission mechanism; and a movable cover at the forward end of said clamp sleeve to expose the slide for attachment or detachment of said transmission mechanism while the slide remains operatively related to the grip, said movable cover forming an abutment for the outer member of the transmission mechanism.

3. A grip control according to claim 1 having means permitting the transmission mechanism to be radially withdrawn from the slide.

4. A grip control according to claim 1 in which the slide has a key-hole slot in which the cable of the transmission mechanism is detachably secured.

5. A grip control of the kind described for actuating transmission mechanism comprising a rotary grip having tubular helically slotted extension; a split sleeve in which said helically slotted extension rotates adapted to be clamped on the outside of the carrier member; a guide in said sleeve outside the twist grip; a longitudinally movable slide working along said guide adapted to permit a transmission mechanism to be detachably connected therewith, said slide being engaged by the helical slot of said tubular extension and moved thereby on rotation of said rotating grip to actuate the cable, raised portions on said sleeve; and a movable cover at the forward end of said clamp sleeve to expose the slide for attachment or detachment of said transmission mechanism while the slide remains operatively related to the grip said cover being secured to the sleeve by a sliding frictional engagement with said raised portions, said cover covering part of the sheath of the transmission mechanism and forming an abutment therefor.

6. A rotary grip control for actuating a transmission mechanism comprising a rotary grip member, a sleeve adapted to be clamped on the outside of a carrier member; a longitudinally movable slide adapted to be detachably connected to a transmission cable;

means in said sleeve for axially guiding said slide; a helical slot in said rotary grip member engaging said slide and moving it longitudinally on rotation of said grip member, a 5 cover which covers the slide when the latter is displaced to the limit of its inward movement, said cover being movable to expose the slide for attachment or detachment of the cable without disassembling the grip mechanism and while the slide is positively retained 10 in engagement with said helical slot.

7. A grip control of the kind described for actuating a transmission mechanism comprising a split sleeve; a guide therein; 15 a rotary grip having a tubular helically slotted extension which is rotatable in said sleeve; said sleeve having one portion thereof adapted to be clamped on a carrier member and having the other portion adapted to 20 frictionally grip said tubular extension to regulate the ease of rotation of said rotary grip; a longitudinally movable slide working along said guide adapted to be connected to the transmission mechanism and to be engaged 25 by the helical slot of said tubular extension and be moved thereby on rotation of said rotary grip to actuate the cable.

8. A grip control according to claim 7 having the sleeve portion which is clamped 30 on the carrier tube at one extreme end of the sleeve and having the other portion of the sleeve free to be adjusted to regulate the friction grip between that portion of the sleeve and the tubular extension of the 35 rotary grip, and means for effecting such adjustment.

9. A grip control of the kind described for actuating a transmission mechanism comprising a one-part clamp sleeve in the 40 form of a nearly complete tubulus; a guide therein; a longitudinally moving slide working along said guide and adapted to be connected to the transmission cable; a rotary grip having a tubular helically slotted 45 extension which is rotatable in said sleeve to move said slide; said sleeve having a thicker front portion adapted to be secured to a carrier member by a tangent screw and a rear portion adapted to frictionally grip 50 said tubular helically slotted extension, said rear portion being adjustable by a tangent screw to regulate the ease of rotation of the rotary grip; and means permitting said transmission mechanism to be attached to or 55 detached from said slide while the slide remains operatively related to the grip.

10. A grip control of the kind described for actuating a transmission mechanism comprising a clamp sleeve made in two 60 parts; means on one side thereof for enabling said parts to be clamped together at one end on a carrier member; a rotary grip having a tubular helically slotted extension which is rotatable in said sleeve; means for 65 adjusting said sleeve at the other end to reg-

ulate the frictional grip between the sleeve and said tubular helically slotted extension; a guide formed by said sleeve; a longitudinally moving slide adapted to be detachably connected to the transmission mechanism and to be engaged by the helical slot of said tubular extension and be moved thereby on rotation of said rotary grip to actuate said transmission mechanism; and a slidable cover engaging the two parts of 70 the clamp sleeve on the other side; said cover when moved permitting said transmission mechanism to be attached to or detached from said slide while the slide remains operatively related to the grip. 75

11. A grip control according to claim 10 in which the sleeve has two of its edges bent back a portion of their lengths for engagement of the sliding cover. 80

12. A grip control according to claim 7 having a liner for adjusting the thickness of the portion of the sleeve which is clamped to the carrier member. 85

13. A grip control according to claim 7 having a split one part liner for adjusting the thickness of the portion of the sleeve which is clamped to the carrier member, and a tangent screw for clamping said liner. 90

14. A grip control according to claim 7 having a liner for adjusting the thickness of the portion of the sleeve which is clamped to the carrier member and means of a steady-pin character for holding said liner to definite position. 95

15. A grip control of the kind described for actuating a transmission mechanism comprising a split sleeve; an open top guide therein; a rotary grip having a tubular helically slotted extension which is rotatable in said sleeve; said sleeve having one portion thereof provided with means to clamp the sleeve on a carrier member and having the other portion to frictionally grip said tubular extension and provided with means for adjusting the friction grip to regulate the ease of rotation of said rotary grip; a longitudinally movable slide working along said guide adapted to be connected to the transmission mechanism and to be engaged by the helical slot of said tubular extension and be moved thereby on rotation of said rotary grip to actuate the cable; and a movable cover for the open top guide adapted to be moved to expose the slide for attachment or detachment of the cable. 100 105 110 115 120

16. A grip control of the kind described for actuating a transmission mechanism comprising a split pressed sheet metal sleeve stamped to shape adapted to be clamped on the outside of a handle bar or like support; a guide in said sleeve; a rotary grip having a tubular helically slotted extension which is rotatable in said sleeve; a longitudinally movable slide working along said guide adapted to be connected to the transmission 125 130

cable and to be engaged by the helical slot
of said tubular extension and to be moved
thereby on rotation of said rotating grip to
actuate the cable; raised portions bent up
5 from said sleeve; and a movable cover at the
forward end of said clamp sleeve to expose
the slide for attachment or detachment of
the cable; said cover being secured to the
sleeve by engagement with said raised por-
10 tions, said cover forming an abutment for
the sheath of the transmission mechanism.

In testimony whereof, I affix my signature.
ALEXANDER HAY NISBET.
